Patented Nov. 19, 1918.

UNITED STATES PATENT OFFICE.

FRANK L. SESSIONS, OF LAKEWOOD, OHIO.

CARBURETER.

1,285,422.

Specification of Letters Patent. Patented Nov. 19, 1918.

Application filed February 19, 1917. Serial No. 149,542.

To all whom it may concern.

Be it known that I, FRANK L. SESSIONS, a citizen of the United States, residing at Lakewood, in the county of Cuyahoga and State of Ohio, have invented certain new and useful Improvements in Carbureters, of which the following is a specification.

My invention relates to carbureters such as are used in connection with internal combustion engines for mixing air and fuel before the resultant mixture enters the explosion chambers of the engine.

It relates particularly to that class of carbureters having a fuel inlet and a primary air inlet of fixed orifice.

The object of my invention is to provide means for varying the relative quantities of fuel and air in order to obtain the best, or desired proportions of fuel and air in the resultant mixture to suit the varying demands of the engine to which the carbureter is connected. For this purpose I have devised new and improved means for varying the relative amounts of fuel and air drawn into the carbureter and have further provided means for delicately adjusting and operating the controlling valves as will be apparent from the following specifications and the accompanying drawings, in which Figure 1 is a side view partly in elevation and partly in section of a carbureter embodying my improvements;

Fig. 2 is a cross section on line II—II of Fig. 1;

Fig. 3 is a cross section on line III—III of Fig. 1.

In the drawings, 1 represents the main body of the carbureter which is provided with the primary air orifice or venturi, 2. 3 is a fuel nozzle, and 4 is a mixing chamber. 5 is a well known type of throttle valve located in the outlet, 6, which connects the mixing chamber, 4, with the engine manifold passage, 7. 8 represents the engine manifold to which the carbureter is secured by bolts, 9, 9.

Connecting the outer end of the venturi with the exterior atmosphere is the air passage, 10, having an opening to the atmosphere at 11. Located in this air passage, 10, is an air inlet valve, 12.

Between the air inlet valve, 12, and the

venturi, 2, there branches from the air passage, 10, an air by-pass, 13, through which the flow of air is controlled by a valve, 14. 55

The fuel nozzle, 3, is connected by a suitable fuel duct, 15, to the fuel supply chamber, 16, which is connected to the fuel supply tank by the pipe, 17. A float, 16^a, is operatively connected to a float valve, not 60 shown, which controls the admission of fuel to the fuel supply chamber. The cover, 16^b, of the fuel supply chamber, 16, may be provided with a small air vent hole, 16^c. A regulating and cut-off valve, 18, controls the 65 flow of fuel from the fuel supply chamber, 16, to the nozzle, 3.

A secondary air inlet is conventionally shown at 19. It is controlled by the customary inwardly opening valve, 20, which is 70 held closed by the adjustable spring, 20'. This valve may be used in connection with my invention if desired, or, it may be omitted entirely; or, the tension of its spring may be adjusted so that the valve will open 75 only when extreme depressions are created within the carbureter by the suction of the engine.

Without reference to the particular means which I have shown for operating the valves 80 12 and 14, but assuming that both of these valves are provided with means for operating them either simultaneously or independently, it will be seen that when valve, 14, is completely closed, my carbureter will operate as any other carbureter which has a 85 fixed air orifice and fixed fuel orifice. The valve, 12, may be used to check the flow of air and thereby increase the relative amount of fuel which will be drawn out of the fuel 90 orifice, 3, by the suction created by the engine.

If, now, with a given opening of the valve, 12, the valve 14, be opened slightly, a portion of the air which enters past the valve, 95 12, will be drawn through by-pass, 13. The difference of pressure which existed between the mixing chamber, 4, and the air passage, 10, will be reduced upon the opening of valve 14, and there will consequently be a 100 different proportion of fuel and air drawn through the orifice, 2. By varying the relative openings of the valves, 12 and 14, it will be seen that any desired proportion of air

and fuel can be drawn into the mixing chamber, 4, within the possible range of the carburetor as it may be designed.

The particular means for operating the valves, 12 and 14, which I have shown in the accompanying drawings, will now be described. Valve, 12, is operatively secured to the shaft, 21, which has bearings in the wall of the air passage, 10, and projects through at one end, 22, where it has operatively fixed upon it the lever, 23. The valve, 14, is operatively secured to the shaft, 24, which has bearings in the wall of the air by-pass, 13, and has adjustably secured to it the lever, 26, by means of the set screw, 26'. The shaft, 24, has one end, 24', extended to form a means for holding the valve, 14, in any desired position while the lever, 26, is being adjusted relatively thereto. Pivoted to the lever, 23, by the pin, 27, is the lever, 28, one end of which is connected to the lever, 26, by the connecting rod, 29. The arm of lever, 28, which is connected by pin, 30, to connecting rod, 29, is the same length as the distance between the centers of shaft, 21, and pin, 27, so that when lever, 28, is in alignment with lever, 23, shaft, 21, and pin, 30, are concentric with each other, and the simultaneous and similar movement of levers, 23 and 28 will produce no movement of lever, 26. If, however, lever, 28, be revolved about its fulcrum pin, 27, into, for instance, the dotted position, 28^a (Fig. 1), valve, 14, will be opened by reason of the displacement of the lever, 26, into its position, 26^a, as shown by dotted lines. If the lever, 28, be placed in such a revolved position as is shown at 28^a, and it be locked to the lever, 23, and lever 23, be now operated, it will be seen that valve, 14, will be operated simultaneously with valve, 12. It is evident that by varying the angular position of lever, 28, relative to lever, 23, the amount of opening of valve, 14, relative to the opening of valve, 12, may be regulated as desired. By changing the angular relation between valve, 14, and lever, 26, by loosening set screw, 26', rotating the lever about shaft, 24, and again tightening set screw, 26', the opening of valve, 14, when levers 28 and 23 are in alignment with each other, may be made any amount desired, or, entirely closed.

Lever, 28, is provided with a curved arm, 28^b, in which there is formed a curved slot, 28^c, concentric with fulcrum pin, 27. A clamp screw, 28^d, threaded into lever, 23, is provided for the purpose of locking lever, 28, in any angular position relative to lever, 23, that is desired.

For operating levers, 23 and 28, I connect to them the rods, 31 and 32 respectively, and these rods are in turn connected in any suitable manner to operating levers, 33 and 34, which may be mounted in any place within

convenient reach of the operator. For this purpose I have shown a stationary bracket, 35, which has a hole bored in it to receive the trunnion, 36, formed upon lever, 33. Lever, 33, is secured in frictional engagement with the bracket, 36, by means of the screw, 37, nuts, 38 and 39, and washer, 40. Lever, 34, is frictionally secured to lever, 33, by means of the knurled head screw, 41. Rods, 31 and 32 are shown pivotally connected to levers, 33 and 34, respectively, by clevises, 42 and 43, and screws, 44 and 45. At 34^a, lever 34 is shown in dotted lines in a position corresponding to the position 28^a of lever, 28.

Should a fixed opening of valve, 14, be desired, the lever, 26, may be secured to shaft, 24, at the proper angle to valve, 14, to give the desired opening when lever, 28, is in alignment with lever, 23, and levers, 23 and 28, may be locked together by screw, 28^d, after which the valve, 14, will not be moved by the operation of lever, 23, as the pin, 30, and shaft, 21, will be concentric. When such an arrangement is to be permanent, the connections between levers, 28 and 34, may be dispensed with. It is evident that the same or any other permanent arrangement of valve, 14, may be secured by first setting it and lever, 28, in the desired positions and then locking lever, 34, to lever, 33, by means of the clamping screw, 41.

It will be understood that any other means for operating valves, 12 and 14, either simultaneously or independently, may be provided without departing from the scope of my invention. It will be further understood that the relative proportions of the levers herein shown, and the means by which they are operatively connected to the main shaft, 21, and by-pass air inlet valves may be altered in any manner found convenient or desirable without departing from the scope of the invention.

In order to further control the flow of fuel from nozzle, 3, which flow is dependent upon the difference of pressure between that in Venturi tube, 2, and that in fuel supply chamber, 16, I provide a fuel pressure regulating tube, or connection 46, connecting the fuel supply chamber, above the level of the fuel, with the air passage, 10. Controlling the passage through tube, 46, is the fuel pressure regulating valve, 47, the stem, 48, of which has secured to it the lever, 49, by set screw, 50. Connecting-rod, 51, operatively joins levers, 49 and 28, as shown in Figs. 1 and 2. Rod, 51, is shown in dotted lines at 51^a, the position it would assume when lever, 28, is in the position shown by dotted lines at 28^a. It will be observed that with the particular arrangement here shown, lever, 49, and consequently valve, 47, has not been appreciably moved by the movement of lever, 28, to the dotted position, 28^a.

It will be also observed that if lever, 28, be locked to lever, 23, in the position shown at 28^a, valve, 47, will be actuated by any movement of lever, 23. This arrangement provides for the opening of valve, 14, in advance of the opening of valve, 47. The opening of valve, 14, will give an additional supply of air to the mixture and the opening of valve, 47, will reduce the amount 10 of fuel. It will be apparent that a proper manipulation of valves, 14 and 47, may be made to result in an extremely delicate variation in the proportions of air and fuel which are drawn into the mixing chamber.

15 When valve, 47, is open the pressure upon the top of the fuel in the fuel supply chamber will be the same as that in the air chamber, 10, and the difference in pressure between that in the venturi, 2, at nozzle, 3, 20 and that in the fuel supply chamber, 16, will be less than the difference between that in the venturi, 2, and the outer atmosphere, by an amount equal to the difference in pressure between that in air chamber, 10, 25 at a point where tube, 46, enters it and the outer atmosphere. This latter, the difference in pressure between that in air chamber, 10, at a point where tube, 46, enters it and the outer atmosphere, is dependent upon the opening of valve, 12, and the resistance to the passage of air from the outer atmosphere to the point in chamber, 10, where tube, 46 enters it. It will be evident that when the engine is running and valve, 47, 30 is open, less fuel will flow through nozzle, 3, than when valve, 47, is shut. The small air vent-hole, 16^c, permits the return of atmospheric pressure to the fuel supply chamber upon the closure of the valve, 47, 35 but the vent hole, 16^c, should be made small enough not to permit air to enter the fuel supply chamber rapidly enough to maintain atmospheric pressure therein while the engine is operating and valve, 47, is open.

40 Lever, 49, may be set upon stem, 48, in any angular relation to valve, 47, so that the valve will open and close in any desired relation to the movement of valves 12 and 14, or either of them. While I have shown only one manner of interconnecting the valve of the fuel pressure regulating tube and the main and by-pass air valves, it will be obvious to those skilled in the art that 45 other means than those shown and described may be employed within the scope of my invention.

If desired, another lever, similar to lever, 28, may be pivoted on pin, 27, and the connecting-rod, 51, be pivoted to it so that the movement of valve, 47, may be effected independently of that of valve, 14.

I claim:

1. In a carbureter having a mixing chamber provided with a fuel inlet, a primary

air inlet and a mixture inlet, said primary air inlet being connected with the outer air by an air inlet passage: a valve in said air inlet passage controlling the admission of air thereto; said mixing chamber and said air inlet passage being connected by an air by-pass around said primary air inlet; a valve in said air by-pass controlling the flow of air therethrough; means for operating said valve in said air inlet passage; 75 means for operating said valve in said air by-pass; and means for operating said valves simultaneously or independently.

2. In a carbureter having a mixing chamber provided with a fuel inlet, a primary air inlet and a mixture outlet, said primary air inlet being connected with the outer air by an air inlet passage: a valve in said air inlet passage controlling the admission of air thereto; said mixing chamber and said air inlet passage being connected by an air by-pass around said primary air inlet; a valve in said air by-pass controlling the flow of air therethrough; two levers connected each to operate one of said valves respectively; and a third lever pivoted to one of said two levers and operatively connected to the other of said two levers, whereby, one of said valves may be operated through the movement of said third lever, and both of 95 said valves may be operated through the movement of that one of the two levers upon which said third lever is pivoted.

3. In a carbureter having a mixing chamber provided with a fuel inlet, a primary air inlet and a mixture outlet, said primary air inlet being connected with the outer air by an air inlet passage; a valve in said air inlet passage controlling the admission of air thereto; said mixing chamber and said air inlet passage being connected by an air by-pass around said primary air inlet; a valve in said air by-pass controlling the flow of air therethrough; and means for operating said valves consisting of a lever operatively connected to the valve in said air inlet passage; another lever operatively connected to the valve in said air by-pass; a third lever pivoted to one of said levers; means operatively connecting the other of 115 said levers to a point on said third lever; said point on said third lever being the same distance from the pivot of said third lever as is the fulcrum of the lever to which said third lever is pivoted.

4. In a carbureter having a mixing chamber provided with a fuel inlet, a primary air inlet and a mixture outlet, said primary air inlet being connected with the outer air by an air inlet passage: a valve in said air inlet passage controlling the admission of air thereto; a fuel supply chamber connected to said fuel inlet, said fuel supply chamber having an opening above the level of the fuel therein; a connecting passage 125

130

between said opening and said air inlet passage; a valve in said connecting passage; means for operating said valve in said air inlet passage; means for operating said 5 valve in said connecting passage, and means for operating said valves simultaneously or independently.

5. In a carbureter having a mixing chamber provided with a fuel inlet and an air 10 inlet; a fuel supply chamber connected to said fuel inlet; a fuel pressure regulating connection between the fuel supply chamber above the top of the fuel therein and said air inlet; an air inlet valve controlling the 15 admission of air to said air inlet; a valve in said fuel pressure regulating connection; means for operating said air inlet valve; means for operating said valve in said fuel pressure regulating connection; and means 20 for operating said valves simultaneously or independently.

6. A carbureter having a mixing chamber provided with a primary air inlet orifice connected with the exterior atmosphere by

an air inlet passage, means for controlling 25 the admission of air to the air inlet passage, an air by-pass around the primary air inlet orifice connecting the air inlet passage with the mixing chamber, means for controlling the flow of air through the by-pass, and 30 means for operating said controlling means simultaneously or independently.

7. A carbureter having a fuel supply chamber, an air inlet and a fuel inlet, a fuel pressure regulating connection between the 35 supply chamber and the air inlet, means for controlling the flow of air through the air inlet, means for varying the size of the opening through the fuel pressure regulating connection and means for operating said 40 means simultaneously or independently.

In testimony whereof I affix my signature in the presence of two witnesses.

FRANK L. SESSIONS.
